Primary Examiner — Steven J Czyz*(74) Attorney, Agent, or Firm* — Barry Choobin; Patent 360(57) **CLAIM**

An ornamental design for a modular umbrella stand, as shown and described herein.

DESCRIPTION

FIG. 1 is a perspective view of the modular umbrella stand; FIG. 2 is a front view thereof; FIG. 3 is a rear view thereof; FIG. 4 is a top view thereof; FIG. 5 is a bottom view thereof; FIG. 6 is a right-side view thereof; FIG. 7 is a left-side view thereof; and, FIG. 8 is a bottom view thereof, in which the bottom cap is removed to show the central hollow tunnel. The broken lines depict portions of the article that form no part of the claimed design.
